UNITED STATES PATENT OFFICE.

ANDREW W. STEIGER, OF HARTFORD, CONNECTICUT, ASSIGNOR TO UNDERWOOD COMPUTING MACHINE COMPANY, OF NEW YORK, N. Y., A CORPORATION OF NEW YORK.

TYPE-WRITING MACHINE.

1,283,348.

Specification of Letters Patent. Patented Oct. 29, 1918.

Original application filed March 30, 1916, Serial No. 87,672. Divided and this application filed March 1, 1917. Serial No. 151,655.

To all whom it may concern:

Be it known that I, ANDREW W. STEIGER, a citizen of the United States, residing in Hartford, in the county of Hartford and State of Connecticut, have invented certain new and useful Improvements in Type-Writing Machines, of which the following is a specification.

This invention relates to typewriting machines, and more particularly to means whereby the pointing off or spacing between figures, as between dollars and cents, and between hundreds and thousands, etc., may be done automatically in the regular course of writing numbers, and is in the nature of an improvement on the application of Frederick A. Hart, No. 79,969, filed February 23, 1916.

In the application above referred to, the mechanism includes an escapement wheel with which coöperates a fixed dog and a loose dog, both supported by a dog rocker, the latter controlled by character keys to effect letter-feed movements of the typewriter carriage. Said application also includes mechanism for effecting a double-space movement of the carriage at a point where it is desired to have a space between figures, by automatically shifting a stop member, which controls the throw of the loose dog, by means of a bail provided with tappets, the tappets being engaged by a projection on a tabulator stop during the travel of the typewriter carriage.

An object of the present invention is to provide means whereby the space skipping mechanism may be manually rendered inoperative. As herein disclosed, this result may be accomplished by swinging the tappeted bail to a position where it will not be engaged by the tabulator stop, by means of a manually operable key arranged at the key-board on the machine.

This application is a division of my application No. 87,672, filed March 30, 1916.

Other features and advantages will hereinafter appear.

In the accompanying drawings,

Figure 1 is a transverse vertical section of the machine, some of the parts being broken away, others being omitted.

Fig. 2 is a detail front elevation of the upper portion of the tabulator plunger bracket, showing part of the means supported thereby for causing the typewriter car-

riage to skip a space at predetermined positions during the travel thereof.

Fig. 3 is a skeleton perspective view illustrating my invention, and showing the connection between the disconnect key and a pivoted frame which supports the tappeted bail.

Fig. 4 is a fragmentary front elevation of the typewriter escapement which shows the parts set so as to allow the typewriter carriage to be moved single letter-space distances.

Fig. 5 is a similar view with the escapement dogs rocked rearwardly.

Fig. 6 is a view similar to Fig. 5, except that the stop member is shifted to effect a double-space movement of the typewriter carriage.

The typewriting machine, except some of the escapement devices which will herein-after be clearly described, is of the usual Underwood construction, in which numeral keys 11 and alphabet keys 12 when depressed, move key levers 13 and 14 respectively, and rock bell cranks 15 to swing type bars 16 upwardly and rearwardly about a fulcrum rod 17, causing types 18 and 19 to print against a cylindrical platen 20 rotatably mounted on the typewriter carriage 21.

The typewriter carriage is under constant tension of the spring drum 22 connected to the typewriter carriage by a strap 23. A rack 24 pivotally mounted on the typewriter carriage at 25, engages with the pinion 26 to rotate an escapement wheel 27 provided with teeth 28. The pinion 26 is connected to the escapement wheel by the usual one-way driving pawls 29. This escapement wheel coöperates with a loose dog 30 and a dog 31 fixed on the dog rocker 32 which is pivotally supported by an escapement bracket 33.

The typewriter escapement, except the double-space feature herein described, is in many respects like that described in the patent to Rice *et al.*, No. 769,804, dated September 13, 1904, and is operated in the following manner.

Each type bar 16 is provided with a heel 35 which, while the type bar is swinging to printing position, moves a universal bar 36 rearwardly against the tension of a spring 37 (Fig. 3) and rocks the dog carrier or rocker 32 against the tension of a spring 38 (Fig. 4). The spring 38 serves the double

function of swinging the loose dog about its pivot 39 when the upper part of the dog carrier is moved rearwardly, and returning the dog carrier to normal position. During the 5 operation of the type bars 16, the dog rocker 32 is caused to vibrate transversely of the escapement wheel 27, thus bringing the teeth 28 of the escapement wheel into coöperation alternatively with the loose and fixed 10 dogs.

When the dog rocker or carrier is moved rearwardly, the loose dog 30 is disengaged from a tooth 28 of the escapement wheel after the fixed dog 31 has moved into a position 15 to engage said tooth and hold the escapement wheel. The loose dog 30, when thus disengaged, is permitted under the influence of the spring 38, to move to a position where it is arrested by a stop 40 (Fig. 20 5), and when the dog rocker is brought back to normal position, the loose dog will be brought into the path of the next succeeding tooth 28 of the escapement wheel 27, and the fixed dog will be withdrawn from 25 the path of the teeth. The wheel being now free, is rotated, causing said succeeding tooth 28 to swing the loose dog about its pivot 39 back to normal position (Fig. 3), against a stop 41 on the dog carrier 32, thereby 30 arresting the carriage after a letter-space movement thereof.

The tabulator, except some of the stops on the stop bar, is of the regular Underwood construction, in which a depression of 35 one of the denominational tabulator keys 45 swings a lever 46 about a fuderum 47, to move the upper end of a plunger 48 into the path of a column stop 49 supported on a stop bar 50 carried by the typewriter carriage. The plunger 48 during such movement releases the typewriter carriage by engaging with a pivoted universal bar 51, causing a downward movement of a link 52 which swings a lever 53 about its pivot 54, 45 and raises the rack 24 out of engagement with the pinion 26, thus setting the carriage free from the escapement devices, and permitting it to be moved by the spring drum 22. The carriage will run until a column 50 stop 49 strikes the projected plunger 48, thereby arresting the carriage at the column position determined by said stop 49, and at the denominational position in the column corresponding to the actuated key 45. In 55 the present case I have shown eight plungers, each one being provided with a key 45 and a lever 46.

Double space movements of the typewriter carriage at predetermined positions during 60 its travel are effected in the following manner.

The stop 40 which normally controls the swinging escapement dog 30 as hereinbefore described, is carried on a shiftable stop mem- 65 ber or lever 95 pivoted on a stud 96 secured

to the escapement bracket 33, the lever being held in position lengthwise of the stud by nuts 97 and 98 (Fig. 3). A second stop 99 on said lever 95 is so positioned that when the lever is rocked from the Fig. 5 position 70 to the position indicated in Fig. 6, the stop 99 is brought into the path of the stop 40. It should be understood that in the Fig. 5 position the swinging dog 30 is arrested by a pin 100 coming in contact with the stop 40, 75 and in the Fig. 6 position the loose dog is arrested by the round portion 101 engaging with the stop 99. If the dog rocker 32 is now rocked to disengage the fixed dog 31 from the escapement wheel, the latter is permitted a double-space movement as one tooth 80 55 has been skipped by the pivoted or loose dog 30.

The shiftable stop member 95 is connected through an arm 103 thereon and a link 110 85 to a bail 107, said bail and stop member being held in normal position by a spring 102, which causes the arm 103 to bear against the escapement bracket 33. The stop member 95 is rocked to its double space permitting position, (Fig. 6) against the tension of the 90 said spring 102, in the following manner.

Those of the tabulator stops 49 which are used to stop the carriage at special zones in which it is desirable to skip the punctuation 95 spaces, are provided with extensions 105 which during the travel of the carriage engage with tappets 106 on the bail 107, which is pivoted to a bail-carrying frame 108 by pivot screws 109. The forward portion of 100 the bail is depressed whenever the extension 105 engages with one of the tappets 106, which causes the stop member 95, connected to said bail by means of the link 110, to be shifted to the Fig. 6 position, where the 105 stop 40 has been taken out of, and the stop 99 brought into, coöperative relation with the loose dog 30.

To explain more clearly the double space movements of the typewriter carriage, let it 110 be assumed that the carriage has reached the ten thousands position in a certain zone. In this position the extension 105 of the tabulator stop 40 will be to the right and adjacent to the middle tappet 106. If we now 115 print in this position, the escapement mechanism will operate as usual to permit the carriage to advance a single letter space distance. This movement of the carriage, however, will cause the tabulator stop to swing the bail 107 and through the link 110, shift the stop 99 to the Fig. 6 position, so that on the next depression of the numeral key (the carriage now being in the thousands position) the loose dog 30 will be permitted to 120 move to the position shown in Fig. 6, upon the rearward movement of the dog rocker, where the dog 30 is arrested by the stop 99. When the dog rocker is allowed to return 125 to normal position, the loose dog will move 130

- back of the adjacent tooth 28 and engage with the next tooth, permitting a double space movement of the escapement wheel, and the carriage will be fed two letter space distances. Automatic double spacing is in like manner effected at the decimal point position and at any other desired points in the computing zone by correspondingly located tappets 106.
- 10 To make the double space mechanism ineffective, which is sometimes desirable, I have found it advantageous to pivot the bail-carrying frame 108 on the tabulator plunger bracket 111, by means of screws 112, 70 so that the upper end of the frame 108 can be moved forwardly to bring the tappets 106 on the bail 107 to the dotted line position A shown in Fig. 1, where the tappets 106 are out of the path of the projection 105 of the 15 tabulator stop 40. The tappets 106 are moved to the dotted line position, above referred to, by pushing the key 80 provided on a thrust rod 81, causing a pin 115 projecting laterally from the thrust rod 81 to 20 rock a bail 116 by means of an arm 117, which is pivoted to the bail at 118 and held against a pin 119 projecting from the bail, by means of a spring 120. When the bail 116 is rocked, it causes a downward pull on 25 a link 121 connected to an arm 122 extending forwardly and laterally from the bail-carrying frame 108.

It will be understood that the stop member 95 is left undisturbed while the tappets 30 are being shifted to the A position, above referred to, the link 110 swinging about its point of connection to 103 of the stop member.

Furthermore the tappets 106 can be locked 40 in their inoperative position by bringing a pin 88 on the thrust rod 81 to a cut-out portion 91 of a slot 89.

The arm 117 is pivoted to the bail 116 and held against the pin 119 by means of the 45 spring 120, thus providing a yielding connection between the thrust rod 81 and the bail 116 to permit a movement of the thrust rod 81 after the bail 116 has come to its final position.

50 It is also to be understood that the bail 116 is pivotally mounted on a rod 123 and is held in place thereon against lateral displacement by collars 124 which are secured to the rod 123.

55 The bail-carrying frame 108, as heretofore mentioned, is pivotally mounted on the tabulator plunger bracket 111 by screws 112. These screws are fixed to said brackets by means of nuts 125 and 126 which are threaded 60 on the screws 112 and allow an adjustment of the frame 108 and thus an adjustment of the tappets 106, so that the latter cooperate with the tabulator stop at the proper time during the travel of the typewriter carriage. It will be seen that the screws 112

have reduced portions 127 which bear in holes 128 in the plunger bracket 111.

Variations may be resorted to within the scope of the invention, and portions of the improvements may be used without others. 70

Having thus described my invention, I claim:

1. In a typewriting machine, the combination of a typewriter carriage, means for propelling it, reciprocating escapement devices which ordinarily allow the carriage to move single letter-space distances, a tabulator stop, means controlled from said tabulator stop for allowing the typewriter carriage to move more than a single letter-space distance at a predetermined position in the travel of said carriage, and means for rendering said tabulator-stop controlled means inoperative. 75

2. In a typewriting machine, the combination of a typewriter carriage, means for propelling said typewriter carriage, reciprocating escapement devices which ordinarily allow the carriage to move single letter-space distances, column-selecting mechanism 80 for the typewriter carriage, means controlled from said selecting mechanism for effecting double-space movement at predetermined positions in the travel of said carriage, said last-mentioned mechanism comprising a 90 tappet, a shiftable stop member to which the tappet is connected, and means for rendering said double space permitting means inoperative by moving said tappet, without disturbing said shiftable stop member. 100

3. The combination with a typewriter carriage and propelling means therefor, of escapement mechanism controlling the letter-feed movements of the carriage to normally effect a single letter-space movement of the 105 carriage at each operation, a bail shifted by the typewriter carriage, a vertical link on which said bail is mounted, a device operated by said link for allowing the carriage to move more than a single letter-space distance by a single operation of the escapement mechanism, and a key adapted to swing said bail on said link to render said device ineffective by swinging the bail clear of the carriage. 110

4. The combination with a typewriter carriage and propelling means therefor, of reciprocating escapement devices which normally allow the carriage to move a single letter-space distance at each operation of 120 said devices, a tabulator stop, means controlled from said stop to permit the typewriter carriage to move more than a single letter-space distance when the carriage reaches a predetermined position relative to 125 said stop, and a key to render said last-mentioned means ineffective.

5. In a typewriting machine, the combination with a paper carriage and propelling means therefor, of escapement mechanism to 130

- permit letter-feed movements of the carriage, character keys operative for printing, means whereby the escapement mechanism is controlled from said keys, to normally effect 5 a single letter-space movement of the carriage at each operation of a key, a tabulator stop, tabulator mechanism comprising a key operative to effect a run of the carriage to a position determined by the tabulator stop, means controlling said escapement mechanism for effecting a double letter-space movement of the carriage when one of said character keys is operated with the carriage in a predetermined position relative to the said tabulator stop, and means 10 to render said double spacing means ineffective.
6. In a typewriting machine the combination of a typewriter carriage and propelling means therefor, of an escapement mechanism normally operative to effect single letter-space movements of the carriage, a series of tappets, a carrier therefor, means carried by the carriage to engage said tappets and 15 actuate the carrier, a device forming part of the escapement mechanism for effecting double letter-space movements of the carriage, a link extending from said device to said carrier and supporting the latter, and a key to render said double spacing means ineffective by swinging said carrier on said link clear of the carriage.
7. The combination with a typewriter carriage and propelling means therefor, of escapement mechanism controlling the letter-feed movements of the carriage, said mechanism comprising a fixed dog and a loose dog, means controlling said loose dog comprising a shiftable stop device, a tappet movably mounted on the machine frame, means moving with the carriage to actuate said tappet when the carriage reaches a predetermined position, connections between said tappet and stop device for shifting the latter, and thereby changing the stop position of said loose dog to effect a double-space letter-feed movement of the carriage, and key-operated means to take said tappet out of the control of the carriage.
8. In a typewriting machine the combination with a carriage and propelling means therefor, of letter-feed mechanism normally operative to effect single letter-space movements of the carriage, tabulator mechanism comprising an adjustable column stop means, means automatically operable to effect a double letter-space movement of the carriage when it reaches a predetermined position in the column determined by the adjustment of said column stop, and means operable at will to render said double letter-spacing means inoperative.
9. In a typewriting machine, the combination with a carriage and propelling means therefor, of letter-feed mechanism for the carriage, including a rack, a pinion meshing with said rack, and dogs to hold the pinion, means shiftably mounted on the machine frame to control said dogs to vary said letter-feed mechanism by varying the throw of a dog while holding the rack and pinion in mesh, means on the carriage to shift said controlling means when the carriage reaches a predetermined position during its letter-feed travel, and thereby automatically cause a double letter-space movement of the carriage, a key, and means operated thereby to render said controlling means ineffective.
10. In a typewriting machine, the combination with a carriage and propelling means therefor, of letter-feed mechanism normally operative to permit single letter-space movements of the carriage, tabulating mechanism comprising an adjustable column stop and a tabulator key operable to cause the carriage to move to a column position determined by the position of adjustment of said stop, numeral keys by which said escapement mechanism is operated, a shiftable device controlling said escapement mechanism, means adjustable with said stop and operable automatically to shift said device when the carriage reaches a position determined by the adjustment of said stop and thereby effect a double letter-space movement of the carriage at a single operation of a numeral key, a key, and means actuated thereby to render said double-spacing means ineffective.
11. In a typewriting machine, the combination with a carriage and propelling means therefor, of numeral keys, types operated thereby to print, a letter-feeding device for said carriage, including a rack on the carriage, a pinion, and dogs for holding said pinion, a tappet movably mounted on the machine frame, means on the carriage to shift said tappet when the carriage reaches a predetermined denominational position in the writing of a number, means operated by said tappet to selectively vary the throw of a dog to effect a double letter-space movement of the carriage while keeping the rack and pinion in mesh, and a key to take the tappet out of the control of the carriage.
12. In a typewriting machine, the combination with a carriage and propelling means therefor, of letter-feed mechanism, including escapement dogs, character keys, means actuated by the keys for operating said letter-feed mechanism, carriage controlled means controlling the letter-feed mechanism to automatically selectively vary the throw of a dog to effect variable spacing between the written characters, and key-controlled mechanism to render said last-mentioned means ineffective.
13. The combination with a carriage and propelling means therefor, of letter-feed mechanism normally operative to effect single letter-space movements of the carriage.

- riage, a machine frame, a swinging frame pivoted thereon, a tappet movably mounted on the swinging frame, means on the carriage to move said tappet transversely of the swinging motion when the carriage reaches a predetermined position, means operated by said tappet to automatically effect a double letter-space movement of the carriage, a key, and a connection between said key and swinging frame for swinging the latter to move said tappet to ineffective position.
14. The combination with a machine frame, of a carriage mounted to travel thereon, means to propel the carriage, letter-feed mechanism controlling the movements of the carriage, a tabulator stop on the carriage, a frame mounted to swing on the machine frame, a tappet bail mounted on said swinging frame in position to be actuated by said tabulator stop during the travel of the carriage, means operated by said bail for automatically effecting a double letter-space movement of the carriage, and a key connected to said swinging frame for swinging the latter to carry said bail out of position to be actuated by the tabulator stop, and thereby silence said double-spacing means.
15. In a typewriting machine, the combination with a traveling carriage and a frame on which it travels, of an escapement device for feeding said carriage letter-spaces, a link connected to said device for causing a double letter-space feed, a bar adjacent said carriage and pivotally supported by said link, a lug on said carriage adapted to strike said bar to make said device feed a double letter-space, a second link pivotally mounted to which said bar is also pivoted, a finger-piece at the typewriter keyboard, a rearwardly-extending bar attached thereto, a rock-arm fast to said second link, and a third link adapted to be drawn down by said last-named bar to swing said rock-arm to carry the first bar clear of the lug.
16. In a typewriting machine, the combination with a traveling carriage and a frame on which it travels, of an escapement device for feeding said carriage letter-spaces, a link connected to said device for causing a double letter-space feed, a bar adjacent said carriage and pivotally supported by said link, a lug on said carriage adapted to strike said bar to make said device feed a double letter-space, a second link pivotally mounted to which said bar is also pivoted, a finger-piece at the typewriter keyboard, a rearwardly-extending bar attached thereto, a rock-arm fast to said second link, and a third link adapted to be drawn down by said last-named bar to swing said rock-arm to carry the first bar clear of the lug.
17. In a typewriting machine, the combination with a traveling carriage and a frame on which it travels, of an escapement device for feeding said carriage letter-spaces, a link connected to said device for causing a double letter-space feed, a bar adjacent said carriage, a frame on which said bar is pivoted, a pair of pivots for said frame, devices for adjustably holding said frame in place on its pivots, a lug on said carriage adapted to strike said bar to make it effective on said link, so that the device will feed a double letter-space, and a finger-piece for swinging said frame adapted to carry said bar clear of said lug.
